UNITED STATES PATENT OFFICE

103,453

DESIGN FOR A DUSTPAN OR THE LIKE

George McStay Jackson, Lake Bluff, Ill., assignor to The Quickwork Company, Chicago, Ill., a corporation of Ohio

Application January 6, 1937, Serial No. 66,928

Term of patent 14 years

To all whom it may concern:

Be it known that I, George McStay Jackson, a citizen of the United States, residing in the city of Lake Bluff, in the county of Lake and State of Illinois, have invented a new, original, and ornamental Design for a Dustpan or the like, of which the following is a specification, reference being had to the accompanying drawing, forming part thereof.

I claim:

The ornamental design for a dustpan or the like, substantially as shown and described.

GEORGE McSTAY JACKSON.
